CLAIM

We claim the ornamental design for a nesting furniture, as shown and described.

DESCRIPTION

FIG. 1 is an exploded front view for a nesting furniture showing my new design, an exploded rear view being a mirror image thereof;

FIG. 2 is an exploded left side view thereof;

FIG. 3 is an exploded right side view thereof;

FIG. 4 is an exploded top view thereof;

FIG. 5 is an exploded bottom view thereof;

FIG. 6 is an exploded top front side perspective view thereof; and,

FIG. 7 is a top front side perspective view for a nesting furniture in an assembled position.

1 Claim, 6 Drawing Sheets

FIG. 1

FIG. 7
